F. AILHAUD

APPARATUS TO STERILIZE LIQUIDS BY MEANS OF ULTRA VIOLET RAYS

Filed April 23, 1923

Inventor:

Patron Attorney

UNITED STATES PATENT OFFICE.

FABIEN AILHAUD, OF BEAUVAIIS, FRANCE.

APPARATUS TO STERILIZE LIQUIDS BY MEANS OF ULTRA-VIOLET RAYS.

Application filed April 23, 1923. Serial No. 633,949.

To all whom it may concern:

Be it known that I, FABIEN AILHAUD, a citizen of the French Republic, residing at Beauvais, Oise, France, have invented certain Improvements in Apparatus to Sterilize Liquids by Means of Ultra-Violet Rays, of which the following is a specification.

The object of my invention is to provide an apparatus to sterilize liquids, especially water and milk, by the action of ultra-violet rays. My apparatus offers the advantages of real efficiency and of great economy. Furthermore, it does not modify the composition of the liquid and does not destroy the valuable components of milk.

Another advantage thereof is that the liquid has not to be clarified before sterilization as is usual with the apparatuses or devices hitherto known.

My apparatus is based on the principle of causing the liquid to pass as a film or thin flow in front of ultra-violet rays. Liquids are thus made more limpid and consequently thoroughly submitted to the influence of radiations.

In order to achieve this purpose, I make the liquids flow through tubes of small diameter and bent several times. My system presents the advantage of compelling the particles to be continually on the move, so that they must unfailingly be submitted to the action of ultra-violet rays.

In order to make my invention more clearly understood, I have illustrated, as an example, an embodiment thereof in and by a drawing appended hereto, which shows a vertical section of an apparatus constructed in accordance therewith.

My apparatus for sterilizing liquids by means of ultra-violet rays comprises a tank 1 for the liquid, such tank communicating through a pipe 2 with a feeding tank 3 itself communicating through a tube 4 with a circular 5.

At the lower part of said tube are arranged a plurality of fine tubes 6 made of cast quartz and bent several times.

Tubes 6 open into a lower circular tube 7 communicating with an outlet tube 8, provided with a cock 9 and with an electric 50 obturator 10.

Circular tubes 5 and 7 are encased in an envelope 11 made of an ultra-violet-ray-retaining material.

Between the circular tubes is arranged an 55 envelope or shell 12 encasing tubes 6, and this envelope also is made of an ultra-violet-ray-retaining material.

In the center of this apparatus is positioned a mercury-vapour lamp 13, carried 60 by two tubes 14 through which run wires 15 and 16.

Wire 16 connected to a solenoid 17 which actuates the obturator 10. Obviously, on the mercury vapour lamp being lit, the solenoid 65 will open the obturator.

Inside the envelope 12 is set a polished metal mirror. Inside the cover and support are also set polished metal mirrors 19 which form two cones intended to reflect the lamp 70 rays onto tubes 6, thus using integrally the rays from the mercury lamp.

What I claim as new and desire to secure by Letters Patent is:—

1. An apparatus to sterilize liquids, characterized by the arrangement of two circular tubes intercommunicating through a plurality of fine tubes made of cast quartz, bent several times, and fed by a main tank of liquid and an intermediate feeding tank; 75 a mercury vapour lamp being positioned in the center of the apparatus, and the circular tubes as well as the cast quartz tubes being encased in an envelope adapted to retain 80 ultra-violet rays.

2. In an apparatus as per claim 1, the fact that the envelope is provided with a polished metal mirror and the cover and support are provided with conical mirrors adapted to reflect the ultra-violet rays on the cast 85 quartz tubes.

FABIEN AILHAUD.
